UNITED STATES PATENT OFFICE.

PHILIP E. YOUNG, OF FAIRHAVEN, MASSACHUSETTS.

HOT-WATER HEATER.

Application filed May 26, 1926. Serial No. 111,899.

The present invention relates to a mechanism to be combined with hot water heaters of the flash type which are heated by gas burners controlled by the pressure of the water in the heater. By the combination embodied in the present invention, a great saving in gas consumption is obtained.

For the purposes of illustration, I have shown my invention in combination with a form of hot water heater of the type described, which is now being sold commercially in this country. In the drawings which illustrate this example, Fig. 1 shows the hot water heater and attachments and Fig. 2 shows the house connections diagrammatically; Fig. 2 is an enlarged sectional view of the gas control mechanism.

The heater which is shown in Fig. 1 is designated by the numeral 10. It contains a coil of pipe 12 in which the water is to be heated by combustion of gas which passes into the heater by a pipe 14. A valve 15 controls the flow of the gas from a pipe 16, and it is understood that the usual form of pilot light is provided which is supplied with gas by pipe 17. 18 is a cold water inlet and 20 is the hot water outlet which leads to faucets 22 in various parts of the house.

30 The valve 15 has a seat 24 and a movable member 26 mounted on a plunger 28. The plunger 28 is tensioned toward the open position by a spring 30 and carries two collars 32 and 34. A bell crank lever 36 contacts 35 with collar 32 so that it can press the plunger 28 into closed position. The bell crank lever 36 is moved by a rod 38 which is normally held by spring 40 in such a position that the valve is closed. The spring 40 has sufficient power to overcome the tension of the spring 30. On the upper end of 40 the rod 38 is a plunger 40 which is actuated by the water pressure in the chamber 42.

As is well known in the art, when any 45 faucet 22 is opened, the pressure under plunger 40 drops and the water pressure above this plunger pushes it down, thereby moving bell crank lever 36 to permit spring 30 to open valve 15. Up to this point, I 50 have described only the operation of parts which are well known in the art.

A second bell crank lever designated by the numeral 44 has a hooked end 46 which engages collar 34 and normally prevents 55 valve 15 from opening, even when the water pressure drops. A lever 48 is adapted to co-

operate with bell crank lever 44 and move hook 46 out of engagement with collar 34. The upper end of lever 48 forms an armature which is moved by a solenoid 50. The 60 solenoid 50 is supplied with electrical energy from any source such as the battery 52. The circuit including the solenoid is normally open but can be closed by pressing any one of a series of electric buttons 54 65 which are located at convenient points adjacent the faucets 22.

In operating the device, a person using hot water, turns on a faucet 22 and presses a button 54, thereby releasing hook 46 from 70 collar 34, permitting the valve 15 to open. Pressure on button 54 can then be immediately released and the electrical circuit opened. If only a small amount of water is to be used, only a little gas will be needed 75 to heat it, and therefore very shortly after the water has been turned on, the faucet 22 is turned off, thereby closing valve 15 and causing hook 46 again to engage collar 34. Faucet 22 is immediately opened and the 80 water will flow through the system, but the valve 15 will remain closed.

I find that with devices of this sort it is possible to heat what may be termed a section of water, which will move through the 85 pipes, pushing the cold water in front of it, and in turn being pushed by cold water. By this arrangement it is only necessary to heat the amount of water desired. For example, if one desires to run a basin of hot 90 water, the gas is turned on for only a few moments, so that the amount of water heated is not enough to fill the pipe all the way from the heater to the faucet. The cold water which will continue to come out of 95 the faucet even after the gas has been turned off is allowed to escape, and as soon as the water becomes hot at the faucet 22, the plug is put in the basin and by the time the basin is filled, the water which had been 100 heated will be used up, leaving the pipe full of cold water, as distinguished from the ordinary practice where the entire pipe is left full of hot water simply to supply one basin full of water at the faucet. Of course, if a 105 large quantity of water is to be used, the gas can be left turned on, even after hot water starts flowing from the pipe 22. Then when almost as much hot water as is wanted has been drawn, the gas can be turned off in the manner described, and the balance of the hot water in the pipe drawn out for use.

It is to be understood that the details shown are given by way of illustration only and that they may be modified in many particulars without departing from the spirit 5 of my invention.

What I claim is:

1. In combination a gas-fired hot water heater, a gas valve, means for operating said valve comprising a water pressure control 10 mechanism, a latch adapted mechanically to prevent the gas valve from opening irrespective of the operation of said water pressure control mechanism, a solenoid adapted to control said latch, a normally open electrical circuit including said solenoid, and 15 circuit closing devices located at the service points for closing said circuit to move said latch.

2. A combination as specified in claim 1, 20 in which the latch when in normal position, will prevent the valve from opening and in

which the electrical circuit must be closed before the valve can open.

3. A combination as specified in claim 1, 25 in which the valve is under tension adapted to keep the valve open and the pressure necessary to close the valve is supplied by mechanism independent of said electrically controlled parts.

4. In a gas-fired hot water heater, the 30 combination of a gas valve, means for opening and closing said valve comprising a water pressure control mechanism, electrically operated means distinguished from said water pressure control mechanism and 35 controllable from remote points adapted to prevent said first-mentioned means from opening said valve and a plurality of manually operated switches for controlling said electrically operated means.

PHILIP E. YOUNG.
